The ornamental design for calendared textured liner, as shown and described.

DESCRIPTION

FIG. 1 is a top plan view of a calendared textured liner showing a first embodiment of my new design;

FIG. 2 is a cross-sectional view of the first embodiment of my new design of a calendared textured liner, taken along line 2—2 of FIG. 1;

FIG. 3 is a top plan view of a calendared textured liner showing a second embodiment of my new design; and, FIG. 4 is a cross-sectional view of the second embodiment of my new design of a calendared textured liner, taken along line 4—4 of FIG. 3.

The broken lines along the border of FIG. 1 indicate that the calendared textured liner has indeterminate length and width. The dash-dot-dash lines within the showing of FIG. 1 indicated one repeat unit of the claimed design, which repeats uniformly throughout the linear.

The broken lines along the border of FIG. 3 indicate that the calendared textured liner has indeterminate length and width. The dash-dot-dash lines within the showing of FIG. 3 indicated one repeat unit of the claimed design, which repeats uniformly throughout the linear.

In the first embodiment, the bottom surface of the claimed design is a mirror image of the design of FIG. 1.

In the second embodiment, the bottom surface of the claimed design is plain and unornamented.
